UNITED STATES PATENT OFFICE.

BENJAMIN N. HARTWELL, OF WESTERVILLE, OHIO, ASSIGNOR TO THE KILGORE MFG. COMPANY, OF WESTERVILLE, OHIO, A CORPORATION OF OHIO.

DETONATING DEVICE.

Application filed October 24, 1921, Serial No. 509,790. Renewed July 5, 1928.

This invention relates to toy detonating devices of the type adapted to explode successively a plurality of caps arranged, preferably, in a continuous strip.

5 An object of the invention is to provide a device in which the caps may be arranged in a magazine adapted to be advanced through the firearm so that the usual hammer may engage the caps successively.

10 Another object of the invention is to provide a magazine in which a strip of caps may be readily inserted for use in a pistol or other type of firearm.

15 A still further object of the invention is to afford a structure which is simple and inexpensive to manufacture, efficient and positive in its operation, and in which the explosions take place entirely within a casing without danger to the operator.

20 Further and more specific objects of the invention reside in the details of construction and in the combination and arrangement of the several parts, which will become more clear as the description proceeds.

25 In the accompanying drawings I have shown the invention as embodied in a toy pistol, although it should be understood that the invention might be applied to other types of firearms and might be considerably varied from the illustrative details of construction shown in the drawings and hereinafter described.

In the drawings:—

30 Fig. 1 is a side elevational view of the pistol.

35 Fig. 2 is a view similar to Figure 1 with the cover plate removed.

Fig. 3 is a horizontal cross section on the line 3—3 of Figure 2.

40 Fig. 4 is a view similar to Figure 3 showing the relation of the parts during the operation of the pistol.

45 Fig. 5 is a vertical section on the line 5—5 of Figure 3 looking in the direction of the arrows.

Fig. 6 is a view similar to Figure 5 looking in the opposite direction.

Fig. 7 is a detail view showing the inside of a case section with the magazine therein.

50 Fig. 8 is an elevational view of the opposite face of the trigger plate shown in Figure 2.

Fig. 9 is a longitudinal sectional view of a modified form of pistol.

Fig. 10 is a cross section on the line 10—10 55 of Figure 9, and

Fig. 11 is an elevational view of a modified magazine construction.

Referring to the drawings for a more detailed description, the pistol comprises a case 60 or shell shaped to form a barrel 10 and a handle or stock 11 to resemble a revolver. The shell is, preferably, cast or stamped and formed in two sections 12, 13, held together by bolts or screws 13'. The section 12 has a 65 marginal flange 14 which meets the inner face of the section 13 and maintains the two sections spaced apart. The barrel is open at its forward end, as indicated at 15, (Fig. 4) and the rear end of the pistol is provided with 70 a magazine inlet opening 16 so that a magazine 17 may be inserted in the barrel and fed therethrough by a mechanism later to be described.

75 A trigger plate 18 (Figs. 2 and 8) is mounted within the casing for reciprocatory movement; and has a forwardly extending portion 19 and a trigger 20. The plate is supported upon the inner face of the casing section 13 by means of a guide rib 21 (Fig. 7) upon the 80 casing section which fits between two spaced guides 22 upon the inner face of the trigger plate. The trigger plate is held in its forward position, shown in Figures 2 and 3, by means of a coil spring 23 anchored at one 85 end, 24, to the casing section 13, and at its other end, 25, to the trigger plate, a stop pin 26 upon the casing section extending through a slot 27 in the trigger plate and limiting its reciprocatory motions in opposite directions. 90

A hammer 28 is mounted upon the trigger plate and has its forked shank 29 extending beneath a strap 30 upon the trigger plate and bent upwardly to prevent withdrawal of the trigger from the anchoring strap. The 95 strap fits loosely about the end of the hammer so as to permit the latter to be raised as the trigger plate is moved rearwardly as indicated in Figure 4. A leaf spring 31 having its rear end 32 fixedly secured in a lug 33 100 upon the trigger plate extends forwardly above the hammer and is fixedly secured to the hammer as indicated at 34. This spring serves to maintain the striker portion 35 of

the hammer projecting through an opening 36 in the forwardly extending portion 19 of the trigger plate and, as the hammer is moved rearwardly by the magazine during the retraction of the trigger plate the spring is flexed, all of which is clearly shown in Figure 4.

Referring to the magazine which serves to raise the hammer as the trigger plate is retracted, it is preferable that the magazine be constructed so as to receive a plurality of caps arranged in strip form. The magazine comprises a face plate 37 having a plurality of openings 38 and arranged adjacent each opening an outwardly and rearwardly inclined tooth 39 which is positioned in advance of the opening. The magazine is also formed with a back plate 40 slightly spaced between the ends of the magazine from the face plate so as to form a chamber to receive a strip of caps positioned within the chamber with a cap registering with each opening. The lower edge of the magazine is provided with a series of shoulders 41 which provide an edge of rack formation, each shoulder being positioned beneath a cap opening. A spring stop or pawl 42 is fixed in the forward edge of the guide rib 21; and extends upwardly and forwardly so that its free end may successively engage the shoulders 41 as the magazine is fed through the barrel.

In using this device the magazine is first loaded with a strip of caps, a detonating cap being located in registry with each opening in the magazine face plate. The magazine is then inserted in the rear barrel opening 16 until its forward edge comes into engagement with the striker portion 35 of the hammer. The trigger plate and hammer are then retracted by means of the trigger and during this movement the striker is moved outwardly, as shown in Figure 3, by the first tooth 39 upon the magazine. As the retraction of the trigger is completed the striker moves past the end of the tooth and is forcibly thrown against the cap in the first magazine opening to explode the cap. During the retraction of the trigger plate and hammer the coil spring 23 has been extended and immediately upon the release of the trigger the spring serves to return the trigger plate and hammer to the position shown in Figure 2. During the return movement of the hammer and trigger plate the striker 35 engages the rear edge of the tooth positioned in advance of the cap which has been exploded and advances the magazine one step through the barrel until the spring pawl 42, which holds the magazine stationary during the retraction of the trigger plate, engages the next shoulder 41 upon the lower edge of the magazine.

The above described operation may be continued successively until the caps within the

magazine are exploded, whereupon the magazine may be withdrawn through the forward opening 15 in the barrel and refilled.

It will be observed that all of the explosions take place within the casing which is entirely closed at the explosion point, and thus no sparks or other flying particles from the caps can leave the casing.

Particular attention is called to the extreme simplicity of the structure above set forth, it being observed that the hammer and its operating spring are mounted entirely upon the trigger plate and may be assembled therewith before insertion of the same within the casing. It will also be noted that the hammer itself serves as the feeding means for the magazine, thus eliminating the necessity for separate feeding mechanism generally employed in toy pistols in which it is possible to explode a plurality of caps in quick succession.

Referring to Figures 9, 10 and 11, there is shown a modified embodiment of the invention in which the principle of operation is the same as in the pistol above described, but in which the mechanical construction is materially simpler, permitting production at considerably less expense. The pistol comprises a casing 43 having a barrel portion 44 and a stock or grip portion 45, the casing being preferably formed from sheet metal; and may be suitably stamped out and bent from a single piece. The casing encloses a trigger plate 46 carrying the trigger 47; and the trigger plate is held within the casing, as by means of a bolt 48 passing through the stock 100 of the casing below the trigger plate. The trigger plate is formed from two strips of metal (Figure 10) suitably bent along a longitudinal line below their upper edges, as indicated at 49, to form a magazine chamber 50 adapted to receive the magazine 51. The two strips of metal forming the trigger plate may be held together by a clip 52 at the rear of the trigger provided with a stop 53 adapted to engage the casing when the trigger plate is moved forwardly, to prevent displacement of the trigger plate during the operation of the pistol. A hammer 54 having its head extending through an opening 55 in one wall of the magazine chamber and a spring shank 56 is held upon the trigger plate by means of clips 57 struck up from the trigger plate. At its forward end the trigger plate is surrounded by a tubular metal clip 58 which has a portion cut away to permit the same to be slipped over the forward end of the magazine chamber. This clip serves as a bearing for the trigger plate as it is reciprocated within the casing, since it has a comparatively tight fit within the barrel 44 and also assists the clip 52 in holding together the strips comprising the trigger plate. The magazine 51 has the openings 38'

54

and the hammer engaging teeth 39' in advance of each opening just as the magazine 17 shown in Figure 7. It will be noted, however, that shoulders 41' are provided along 5 the upper edge of the magazine so as to engage successively a spring holding-pawl 60 mounted within the barrel of the casing and held therein by a clip 61 struck out of the casing.

10 A strip of caps is placed upon the magazine with the caps registering with the openings 38' and the curved edge portions 51' of the magazine engaging the margin of the strip of caps and holding it in position. The 15 magazine is inserted in the chamber 50 through its open rear end and the trigger plate is then reciprocated forwardly and rearwardly in the casing to advance the magazine through the chamber and explode 20 the caps. As the trigger plate is moved rearwardly, the hammer head 55 engages a projection 39' upon the magazine and is raised, the magazine being held stationary by the retaining pawl 60 which engages a shoulder 41 25 upon the magazine. Continued movement of the trigger plate results in the hammer head striking the cap registering with the opening at the rear of the projection and exploding the cap. Upon subsequent forward 30 movement of the trigger plate, the hammer head engages the projection which it has previously passed over and carries the magazine forwardly with the trigger plate. Continued repetition of the above movements 35 causes successive explosions of the caps in the magazine and a feeding movement of the magazine through the chamber and barrel until the caps have all been exploded, whereupon the magazine may be withdrawn from 40 the open forward end of the chamber to be refilled.

It should be understood that numerous modifications may be made in the illustrated and described structure without departing 45 from the range of the invention.

I claim:

1. A device of the class described comprising a hammer, means for bodily reciprocating said hammer, means operative during the bodily movement of the hammer in one direction to move the same at an angle to the line of said bodily movement, and yielding means for returning said hammer when given said last mentioned movement to cause the same to strike a cap.

2. A device of the class described comprising a magazine adapted to hold a plurality of detonating caps, a hammer, means for imparting a reciprocatory movement to said hammer, and means upon the magazine operative during the movement of the hammer in one direction to cause the same to strike against a cap and operative during the reverse movement to cause the magazine to be advanced.

3. A device of the class described comprising a magazine adapted to hold a plurality of detonating caps, a hammer, means for imparting a reciprocatory movement to said hammer, and means upon the magazine operative during the movement of the hammer in one direction to cause the same to strike against a cap and operative during the reverse movement to cause the magazine to be advanced by said hammer.

4. A device of the class described comprising a magazine adapted to hold a plurality of detonating caps in strip form, a hammer, means for imparting a reciprocatory movement to said hammer, and means upon the magazine operative during the movement of the hammer in one direction to cause the same to strike against a cap and operative during the reverse movement to cause the magazine to be advanced by said hammer.

5. A device of the class described comprising in combination a magazine adapted to contain a plurality of detonating caps, a hammer having a reciprocatory movement and means adapted to engage said hammer during its movement in one direction to raise and release the hammer to cause the same to strike a cap and to engage the hammer during its movement in the opposite direction to cause the magazine to be moved.

6. A device of the class described comprising in combination a magazine adapted to contain a plurality of detonating caps, a hammer having a reciprocatory movement, and means upon the magazine adapted to engage said hammer during its movement in one direction to raise and release the hammer to cause the same to strike a cap and to engage the hammer during its movement in the opposite direction to cause the magazine to be moved.

7. A device of the class described comprising in combination a magazine adapted to contain a plurality of detonating caps, a hammer having a reciprocatory movement, a trigger plate for reciprocating said hammer, and means upon the magazine adapted to engage said hammer during its movement in one direction to raise and release the hammer to cause the same to strike a cap and to engage the hammer during its movement in the opposite direction to cause the magazine to be advanced.

8. A device of the class described comprising in combination a magazine adapted to contain a plurality of detonating caps, a trigger plate having a reciprocatory movement, a hammer mounted upon and movable with said trigger plate, and means upon the magazine adapted to engage said hammer during its movement in one direction to raise and release the hammer and to engage the hammer during its movement in the opposite direction to cause the magazine to be moved.

9. A device of the class described comprising

- ing a barrel, a magazine adapted to hold a plurality of detonating caps and to be fed through said barrel, a trigger plate having a reciprocatory movement, a hammer movable by said trigger plate, means for maintaining the magazine stationary while the hammer is being moved in one direction by said trigger plate, means for raising and releasing said hammer during said movement, and 5 means upon the magazine adapted to be engaged by a member upon the trigger plate during its movement in an opposite direction to cause a feeding movement of the magazine through the barrel.
10. A device of the class described comprising a barrel, a magazine adapted to hold a plurality of detonating caps and to be fed through said barrel, a hammer having a reciprocatory movement longitudinally of said magazine, a trigger for moving said hammer, means upon the magazine for raising the hammer to cause the same to strike a cap when the hammer is moved by the trigger in one direction, means for maintaining the magazine stationary during said movement, the hammer engaging the said means upon the magazine during the hammer movement in the opposite direction to advance the magazine.
15. 11. A device of the class described comprising a magazine adapted to receive a plurality of detonating caps, a hammer having a reciprocating movement, a trigger for moving the hammer in one direction, and a single means upon the magazine for causing the hammer to be raised to strike a cap during its movement in one direction and to engage the hammer during its movement in the opposite direction whereby the magazine is advanced during said last mentioned movement.
20. 12. A device of the class described comprising a magazine adapted to receive a plurality of detonating caps in strip form, a hammer having a reciprocating movement, a trigger for moving the hammer in one direction, and a single means upon the magazine for causing the hammer to be raised to strike a cap during its movement in one direction and to engage the hammer during its movement in the opposite direction whereby the magazine is advanced during said last mentioned movement.
25. 13. A magazine for use in toy pistols comprising a plate adapted to serve as a backing element for a strip of caps whereby the caps may be exploded, and having means adapted to retain the strip against substantial longitudinal or transverse movement on the plate.
30. 14. A magazine for use in toy pistols comprising a face plate having a plurality of openings therein, and means on the back of said plate forming a compartment to receive and retain a strip of caps, said compartment being common to a plurality of said openings.
35. 15. A magazine for use in toy pistols comprising a face plate having a plurality of openings therein, and a hammer-raising tooth adjacent each opening, said magazine having means behind said plate adapted to hold a strip of caps with each cap in registry with an opening.
40. 16. A toy pistol comprising in combination a barrel, a magazine adapted to contain a plurality of detonating caps and to be fed through said barrel, a trigger plate having a reciprocatory movement longitudinally of said magazine, a spring pressed hammer mounted upon said trigger plate and movable therewith, a plurality of spaced upwardly inclined teeth upon said magazine adapted to raise said hammer during its movement in one direction, means for maintaining the magazine stationary during said hammer movement, said hammer engaging the teeth upon the magazine during its movement in the opposite direction to cause an advance of the magazine through the barrel.
45. 17. A toy pistol comprising in combination a casing having a barrel portion and a grip portion, a reciprocable trigger plate having a hammer thereon within said casing, said trigger plate having a magazine chamber, a magazine adapted to hold a plurality of caps, and means for successively exploding said caps and feeding said magazine through said chamber and the barrel portion of the casing as said trigger plate is reciprocated.
50. 18. A toy pistol comprising in combination a casing having a barrel portion and a grip portion, said casing being formed of a single piece of sheet metal, a reciprocable trigger plate having a hammer thereon within said casing, said trigger plate having a magazine chamber, a magazine adapted to hold a plurality of caps, and means for successively exploding said caps and feeding said magazine through said chamber and the barrel portion of the casing as said trigger plate is reciprocated.
55. 19. A toy pistol comprising in combination a casing having a barrel portion and a grip portion, said casing being formed of a single piece of sheet metal, a reciprocable trigger plate having a hammer thereon within said casing, said trigger plate having a magazine chamber, a magazine adapted to hold a plurality of caps, means upon the barrel for holding the magazine stationary as the trigger plate is moved in one direction, means for moving the magazine with the trigger plate as the latter is moved in the opposite direction, and means for successively exploding said caps and feeding said magazine through said chamber and the barrel portion of the casing as said trigger plate is reciprocated.

54

1,703,446

5

20. A magazine for use in toy pistols, comprising a plate, and means on said plate for engaging a strip of caps adjacent its ends and holding said strip in fixed position on said plate. 5
21. A magazine for use in toy pistols comprising a plate having a plurality of openings therein, a plurality of lugs extending outwardly from the face of said plate, each 10 lug being positioned adjacent an opening, and a compartment at the rear of said plate common to a plurality of said openings and adapted to receive and retain a continuous strip of caps. 10
22. A magazine for use in toy pistols comprising a plate, hammer engaging projections on said plate and end flanges extending outwardly from and over the plate to engage the extremities of a strip of caps and retain the 20 same on said plate. 15
23. A magazine for use in toy pistols comprising a plate, hammer engaging projections on said plate, end flanges extending outwardly and over the plate to engage the extremities 25 of a strip of caps, and a side flange extending outwardly from and over the plate to engage a side of the cap strip, said flanges serving to retain the strip upon said plate. 20
24. A magazine for use in toy pistols comprising a plate, and means extending outwardly and over the plate from an edge thereof to engage a strip of caps adjacent its margin and to retain the same in fixed position on said plate. 30
25. A device of the class described comprising a hammer, means for bodily reciprocating said hammer along a substantially rectilinear path, means operative during the 35 bodily movement of the hammer in one direc- tion to move the same at an angle to the line of said bodily movement, and yielding means for returning said hammer when given said last mentioned movement to cause the same to strike a cap. 40
26. A device of the class described comprising a hammer, means for bodily reciprocating said hammer, means operative during the movement of the hammer in one direction to move the same at an angle to its path of 45 bodily movement and to release the same, and spring means for actuating the hammer when released. 50
27. A device of the class described comprising a hammer, a carrier for said hammer reciprocable along a rectilinear path, a trigger 55 operatively associated with said hammer for moving the same in one direction, means adapted to raise and release said hammer as the holder moves, whereby it may strike a cap positioned adjacent the movable path of 60 said holder, and spring means for actuating said hammer when released. 60
28. A device of the class described comprising a hammer, a carrier for said hammer reciprocable along a rectilinear path, a trigger 65 operatively associated with said hammer for moving the same in one direction, spring means for moving the holder in the opposite direction, means adapted to raise and release said hammer as the holder moves, whereby it 70 may strike a cap positioned adjacent the movable path of said holder, and spring means for actuating said hammer when released. 70

In testimony whereof I have hereunto set 75 my hand.

BENJAMIN N. HARTWELL.
